UNITED STATES PATENT OFFICE.

STEPHEN FREEMAN, MICHAEL FREEMAN, AND WILLIAM E. DAVIS, OF RACINE, WISCONSIN, ASSIGNORS TO THE S. FREEMAN & SONS MANUFACTURING COMPANY, OF SAME PLACE.

FEED-CUTTER.

SPECIFICATION forming part of Letters Patent No. 429,482, dated June 8, 1890.

Application filed August 6, 1888. Serial No. 282,030. (No model.)

To all whom it may concern:

Be it known that we, STEPHEN FREEMAN, MICHAEL FREEMAN, and WILLIAM E. DAVIS, of Racine, in the county of Racine, and in the State of Wisconsin, have invented certain new and useful Improvements in Feed-Cutters; and we do hereby declare that the following is a full, clear, and exact description thereof.

- 10 Our invention relates to feed-cutters, and will be fully described hereinafter.
In the drawings, Figure 1 is a side view of our device, showing the driving mechanism. Fig. 2 is an elevation of the opposite side from that shown in Fig. 1. Fig. 3 is a broken plan view. Fig. 4 is a section on line 4 4, Figs. 1, 2, and 3, with the nest of cog-wheels removed. Fig. 5 is a vertical cross-section of the gear-wheel for driving the lower feed-roll shaft, 20 showing means for locking it in adjustment. Fig. 6 is a face view of a portion of the same. Fig. 7 is a vertical section similar to Fig. 5, but showing a modified form of lock. Fig. 8 is a section on line 8 8, Fig. 7; and Fig. 9 is a 25 section on line 9 9, Fig. 7.

A is the shaft of the cutter-head, which shaft has first hung to it an arm B, and outside of that arm carries pinion C. The arm B has an elbow, from which a stud D projects, and 30 this stud carries a cog-wheel E, on the back of which is a pinion F. The lower end of the arm B carries another elbow, which is formed with a stud G, that carries a pinion G', and below the stud G the arm has a 35 curved projection H, which is connected by a link I with the lower end of a lever L, which lever is provided with a pawl M for engagement with a rack N. The shaft O, that carries the lower feed-roller P, is provided with a 40 nest of cog-wheels a b c, and on its opposite end this shaft passes through one end of a link d, and outside of this link carries a cog-wheel E'. The other end of link d fits loosely on a stud formed on the lower end of a link d', and 45 the upper end of this link is fitted on a shaft O' of the upper feed-roller i, which carries outside of the link d' a sprocket-wheel I', while the stud on the lower end of link d' carries outside of link d a sprocket-wheel j,

which is cast on the inner face of the cog-wheel k. The link d fits loosely on the shaft O and the stud of link d', and the two sprocket-wheels are connected by a drive-chain m, the result being that no matter how much the shaft O' may be lifted in the slot P' 55 in the cutter-box q, the cog-wheels E' and k are always in contact and mesh with each other.

The bearings R R of the shaft of the upper feed-roller i are adapted to slide in slots P' in 60 the cutter-box, and are provided with hangers r, that are slotted to receive studs t on the curved ends of arms S S, that project from a shaft T, that is loosely journaled in the sides of the box q, and these arms and shaft T 65 serve to maintain the roller i in a horizontal position and parallel with roller P.

In operation it is only necessary when the feed is to be changed to throw the pinion G' 70 out of gear by means of lever L, and then to adjust the nest of gearing a b c in or out to bring any particular one of said gears in line with pinion G', and then by operating lever L to adjust pinion G' into mesh with the proper gearing of the nest. The nest of gearing 75 is formed with the usual hub a', which is splined on the shaft O, and this shaft is formed with indentations b' to receive the lower end of a locking-bolt c', that is fitted in a housing c² 80 in the face of the gear c. A thumb-piece c³ projects from bolt c' through a slot in the front of the housing, and the bolt is forced inward toward the center of the gearing by a spring c⁴, that surrounds it, and is confined 85 between the hub of the thumb-piece and the upper portion of the housing. The hub a' fits rather loosely on shaft O, and when the nest a b c is to be adjusted it is only necessary to lift the bolt c' out of whatever indentation it may happen to be in and then draw 90 the nest out or thrust it in until the proper indentation comes under the bolt, and thus the nest will be securely locked in just the desired position on the shaft.

Instead of using a bolt, as in Fig. 5, we may 95 use a flat spring b², which is attached at its inner end to the hub a', and, passing through an opening in the nest, has a prong b³, that en-

gages notches in the spline b^4 . The prong may be stamped out of the spring, so as to leave a thumb-piece b^5 , by which the prong may be lifted when desired.

5 Having thus fully described our invention, what we claim as new, and desire to secure by Letters Patent, is—

In a feed-cutter, the combination, with the cutter-shaft carrying a gear-pinion, and an 10 arm or hanger hung pivotally upon said shaft and having two opposite bends or angles and an extended lower end, of intermeshing gear-wheels turning upon studs at the angles of said arm, a differential gear-wheel mounted adjust- 15 ably upon the adjacent end of the lower feed-roll shaft, and having a spring-catch engaging

recesses in said shaft, and a lever pivoted upon the machine-frame and operatively connected with the lower end of the gear-carrying hanger, so as to throw the lower gear thereof 20 into and out of engagement with said differential gear, substantially as set forth.

In testimony that we claim the foregoing we have hereunto set our hands, at Racine, in the county of Racine and State of Wisconsin, 25 in the presence of two witnesses.

STEPHEN FREEMAN.
MICHAEL FREEMAN.
WM. E. DAVIS.
